UNITED STATES PATENT OFFICE.

HARRY A. HIGGINS, OF DETROIT, MICHIGAN, ASSIGNOR TO DIAMOND POWER
SPECIALTY CO., OF DETROIT, MICHIGAN.

BLOWER FOR BOILERS.

1,016,993.

Specification of Letters Patent. Patented Feb. 13, 1912.

Application filed March 23, 1911. Serial No. 616,358.

To all whom it may concern:

Be it known that I, HARRY A. HIGGINS, a citizen of the United States of America, residing at Detroit, in the county of Wayne 5 and State of Michigan, have invented certain new and useful Improvements in Blowers for Boilers, of which the following is a specification, reference being had therein to the accompanying drawings.

10 This invention relates to boiler-flue cleaners or blowers, and especially to that class thereof which may be applied to the setting of what is generally known as the "vertical type", and it has for its object the provision 15 of a pair of such devices which may be brought into operation on opposite sides of the boiler, but obtain their steam-supply from the same stand pipe.

The invention has, furthermore, for its 20 object the improved articulation and organization of the steam-pipes or tubes, whereby the latter may be projected into the setting, or removed therefrom when not in use, and thus permit the "cleaner-openings" to be closed against loss of draft.

25 Further objects of the invention will hereinafter appear and be particularly defined in the claims.

The invention has been clearly illustrated 30 in the accompanying drawings, in which similar characters denote similar parts, and in which—

Figure 1 is a vertical central section of a boiler of the "vertical water tube type"; 35 Fig. 2 represents a horizontal section thereof, on line 2, 2 of Fig. 1; Fig. 3 is a perspective diagram of the steam-supply pipe, its articulated branches, and the jet tubes; Fig. 4 is an end view of one of the blower 40 heads, and Fig. 5 represents a section thereof, on lines 5, 5 of Fig. 4.

Briefly stated, the present invention comprises one or more steam-carrying or blower-tubes disposed at substantially diametrically opposite sides of the boiler, and each having a blower or distributing head which has jet openings through which steam may be blown along the vertical boiler tubes, and which may be swung horizontally to reach several of these tubes. Usually there are two or more of these jet-tubes side by side in a horizontal plane, and in the present instance means are provided for swinging each set of jet-tubes simultaneously. The present organization is also

such that the set of jet tubes may be entered into, or withdrawn out of the boiler setting at once, each set being furthermore controlled, as to its steam supply, by a valve, without interfering with the steam supply 60 and valve for any other set.

Referring to the drawings, the steam boiler is in the present instance of the "vertical" type, and comprises water tubes 10 in which the water is heated by the products of combustion passing along the same within one half 11 of the boiler setting 12 which is separated from the other half 13 thereof by a partition or baffle wall 14. The setting 12 is of the usual hollow cylindrical shell 70 construction, and is provided with sets of horizontally aligned blower-openings 15, 16 formed in the respective flue-containing halves of the setting, and adapted to be closed by suitable plates 15', 16'. 75

In the preferred form thereof shown, my improved blower comprises a vertical main steam-supply pipe 20 connected with the steam dome 10' of the boiler and pivotally supporting branch pipes 21, 22 extending 80 toward the opposite sides of the boiler so that they may be swung in an arc horizontally around the axis of the pipe 20. The outer ends of these pipes are provided with short nipples 23, 24 which in turn 85 pivotally support leaders 25, 26, extending across the sides of the boiler setting and adapted to swing toward and away from the same. The leader 25 has a valve 27 to control the passage of steam for a series of 90 jet tubes 29, each of which is mounted for horizontal swinging movement around a riser 31 in communication with the leader 25. At its other end each tube 29 opens into a jet or distributing head H (see Figs. 4 and 95 5) which consists substantially of a chambered casing, the wall of which is perforated to form jet-openings j, j' so disposed as to blow steam over a considerable length of the vertical boiler-tubes 10. Each of the 100 jet-tubes 29 has a rearwardly-extending arm 33, the ends of these arms being connected by a link 35 which is provided with a handle 37 whereby the entire set of jet-tubes may be swung horizontally around the risers 31 105 within the limits of the openings 16, three of which being shown on the right hand side of the boiler. Similar blowing devices are adapted to be applied to the left side of the boiler setting which has its pairs of blower 110

apertures 15 adapted to receive the distributing heads H' carried on the ends of jet tubes 30 which may be swung horizontally on risers 28 by a handled link 36 provided 5 with a handle 38.

Usually the boiler settings are provided with a plurality of superposed blower-apertures so that the tubes may be cleaned for their entire length, and it is to be understood 10 that my improved blowers may be applied to any of said openings as may be deemed desirable or necessary.

By virtue of the articulation of the several components of the blower, it is evident 15 that the several blower-heads may be readily inserted or withdrawn through their respective apertures, that the steam jets will blow off the surface of the boiler tubes within range for a considerable distance of their 20 lengths, and that the effect of the blowers may be directed to different boiler-tubes within the horizontal sweep of the jet-heads.

Many changes may be made in the particular construction and organization of the 25 several parts of the blower system, especially in the manner of uniting the movable pipes, without departing from the spirit of the invention.

I claim:

30 1. A blower for boilers comprising a steam supply-pipe, a leader pivotally connected thereto, a jet tube pivoted on the leader to swing transversely of the boiler tubes, and a 35 head on said jet tube having perforations disposed in a plane parallel to the boiler tubes.

2. A blower for boilers comprising a steam supply-pipe, a leader pivotally connected thereto, a jet tube pivoted on the leader to swing transversely of the boiler tubes, a head 40 on said jet tube having perforations disposed in a plane parallel to the boiler tubes, and means for controlling the passage of steam through the leader.

3. A blower for boilers comprising a steam supply-pipe, a leader pivotally connected thereto, a series of jet tubes pivoted on the leader to swing transversely of the boiler tubes, a head on each jet tube having perforations disposed in a plane parallel to the 50 boiler tubes, and means for swinging said tubes simultaneously.

4. A blower for boilers comprising a steam supply pipe, a branch pivoted thereto, a leader pivoted on the branch pipe to swing 55 transversely of the boiler-tubes, a jet tube pivoted on the leader, and means for swinging said jet tube.

5. The combination with the setting of a vertical boiler having apertures at opposite 60 sides, of a blower therefor comprising a stationary vertical steam-supply pipe, branches extending horizontally to opposite sides thereof, leaders pivoted for horizontal swing on said branches, and jet tubes pivoted for 65 horizontal swing on said leaders.

In testimony whereof I affix my signature in presence of two witnesses.

HARRY A. HIGGINS.
